UNITED STATES PATENT OFFICE

98,683

DESIGN FOR A LEVEL SUPPORT

Adolph Langsner, Chicago, Ill., assignor to Eugene Dietzgen Company, Chicago, Ill., a corporation of Delaware

Application August 25, 1934, Serial No. 53,061

Term of patent 14 years

To all whom it may concern:

Be it known that I, Adolph Langsner, a citizen of the United States, residing at Chicago, Cook County, Illinois, have invented a new, original, and ornamental Design for a Level Support, of which the following is a specification, reference being had to the accompanying drawing, forming part thereof.

Figures 2 and 3 are side elevations of the same taken at right angles to each other.

I claim:

The ornamental design for a level support as shown,

ADOLPH LANGSNER.
